US0D1072537S

(12) **United States Design Patent** (10) **Patent No.:** **US D1,072,537 S**
(45) **Date of Patent:** **** Apr. 29, 2025**

(54) **LOCKER**

(71) Applicant: **Luoyang Hanxing Furniture Co., Ltd.**, Luoyang (CN)

(72) Inventor: **Xiaotao Ma**, Luoyang (CN)

(73) Assignee: **Luoyang Hanxing Furniture Co., Ltd.**, Luoyang (CN)

(**) Term: **15 Years**

(21) Appl. No.: **29/971,865**

(22) Filed: **Nov. 6, 2024**

(30) **Foreign Application Priority Data**

Sep. 14, 2024 (CN) 202430592070.5

(51) **LOC (15) Cl.** **06-04**

(52) **U.S. Cl.**

USPC **D6/671.1**

(58) **Field of Classification Search**
